Application May 13, 1958, Serial No. 734,941

7 Claims. (Cl. 197—18)

The present invention relates to a typewriter having a drive mechanism to provide the force of impact.

One of the principal objects of the invention is to provide a typewriter in which the impact of the types is derived from an electric motor and which operates very rapidly and reliably.

This object is in the main achieved by the type bars being mounted on a rotor revolving with a regular speed of rotation and provided with organs holding the type bars in neutral position on the rotor and permitting them to swing out one at a time, so that during the rotation they will impinge against the sheet of paper placed on the cylinder of the typewriter. In order to make the type bar swing out by depression of the corresponding key, each key is connected with an engagement device which, when the key is depressed, will engage a projecting arm on the rotor, so that this arm will cause the type bar concerned to swing outwards. Otherwise the typewriter may be constructed in the usual manner, for instance with springs to carry the keys back to neutral position and with a carriage bearing the turntable cylinder.

Other objects and details of the invention will appear from the following specification under reference to the drawing in which

Fig. 1 shows in perspective a typewriter according to the invention.

Fig. 2 in diagram a rotor for the typewriter with appurtenant keys,

Fig. 3 a section through line 3—3 in Fig. 2,

Fig. 4 a section through line 4—4 in Fig. 1,

Fig. 5 a section through line 5—5 in Fig. 1,

Fig. 6 a segment of Figs. 3 and 4 on an enlarged scale, and Fig. 7 a segment of Fig. 4 on an enlarged scale.

In the drawing 1 designates types, each of which is fastened to a short arm 2 mounted on a short axle 3. Axles are turnably mounted in a part 4 of the frame of a rotor connected with an electric motor. Axles 3 are mounted on a cylindrical surface in relation to the axis of the rotor and each carries a cylinder-shaped locking device 5 provided with a deep notch 6 and in connection therewith a curved surface 7 ending in a notch 8. The rotor is provided with two sets of types with appurtenant arms 2, axles 3 and locking devices 5, the two sets being placed one on each side of a central plane at right angles to the rotor axis. The arms 2 are placed at a tangent to the said cylinder surface and at an oblique. Axles 3 are almost parallel to the rotor axis.

The frame of the rotor further carries axles 10 extending parallel to the rotor axis and situated on a cylindrical surface of smaller diameter than that on which axles 3 are mounted. Each axle 10 carried an outward projecting arm 11, which in Figs. 4 and 6 are shown in engagement with the notch 6. Each axle 10 is further provided with a radial, outward projecting arm 12. These arms 12 are distributed over the length of the rotor.

At the side of the rotor on the frame 24 of the typewriter, key arms 13, 14, are mounted on pivots 15. To one arm a key 16 is fixed. The other arm carried an

upwardly projecting push rod 17 on which a link 18 is turnably mounted carrying an engagement device in the form of an arm 19. A spring 20 fastened to the frame of the typewriter will constantly press against an expansion of arm 19. On one side of arm 19 a compression spring 21 is mounted and on the other side a fixed rest 22. Each arm 19 is situated in the plane of travel of the organ 12 actuating it. Close to the rotor and parallel thereto a turnable cylinder 23 is mounted.

When the typewriter is in operation the rotor is by means of an electric motor and a gear transmission not shown in the drawing but placed in a casing 25 on the frame, made to rotate with considerable speed. The type bars 2 are held in neutral position by the engagement of the arm 11 in the notch 6. When a key 16 is depressed the push-rod 17 will be lifted and thus also arm 19. When the corresponding arm 12 on the rotor during the rotation reaches arm 19, it will impinge against that arm and thereby be forced to the rearward whereas arm 19 will swing forward against spring 21. By the further revolution of the rotor arms 12 and 19 will disengage and arm 19 will under the pressure of spring 21 swing over until it impinges against rest 22 where it is held by the friction exercised by spring 20. When the key 16 is disengaged and by means of springs, not shown in the drawing, is moved upwards to its initial position, arm 19 will by organs not shown in the drawing again return to position in extension of push-rod 17. When arm 19 has been swung over against rest 22 it will be outside of the track of arm 12, and the latter cannot therefore be actuated again even if the key 16 is kept depressed for more than one revolution. By the swing of arm 12 axle 10 will be turned so that arm 11 will be disengaged from the deep notch 6. Thereby the locking device 5 will be released and arm 2 and type 1 may swing outwards, and due to the centrifugal power created by the rapid rotation this swinging motion will start at once and continue until notch 8 engages the hook at the end of arm 11. This position of arm 2 is shown in Figs. 3 and 6, in the latter by stippled lines. By the rapid rotation of the rotor the type is made to impinge against the cylinder 23, as shown in Fig. 3. By the rebound, or possibly by means of special controls, arm 2 is after the impact caused to return to its initial position and the hook of arm 11 will again engage the deep notch. For this purpose arm 11 may be spring-loaded. The typewriter will then be ready for depression of the same or another key. The rate of rotation may be adjustable. It should be so high that at normal writing speed two keys will not be depressed during one revolution of the rotor. A locking mechanism may be provided to prevent the simultaneous depression of two keys. In order that types 1 in each of the two sets may be made to impinge against the cylinder at the same spot, namely in plane 9, axles 3 may be slightly inclined so that during the swing the types will move a slight distance in the axial direction of the rotor. Axles 3 may form tangents to a helical line on the cylindrical surface concerned, or they may have one end inclined inwards in the cylinder surface and the other end outwards, or they may be inclined in both senses. The arrangement of the axles in inclined position will make it possible to have the types situated at an angle when in neutral position, whereby the diameter of the rotor may be made as small as possible. The longitudinal motion of the types may also be brought about by an axial arrangement of the axles when the latter are controlled in their bearings by a helical groove. Each arm 2 may have two, or possibly more, types offset in relation to each other in the longitudinal direction of arm 2. Correspondingly the cylinder may in the usual manner be movable in the vertical direction to receive the impact of the different types.

The embodiment shown in the drawing and described above is to be considered only by way of an example, as many variations may be contemplated within the scope of the invention. The embodiment described makes it possible to have the type released during the rotation wipe against an ink pad, which may be a rotating pad, so as to obviate the use of a typewriter ribbon.

I claim:

1. Typewriter, comprising a frame, a cylinder turnably mounted on the frame, a rotor mounted in the frame with its axis of rotation parallel to the axis of rotation of the cylinder, a number of type bars pivoted on the rotor in such a manner that they may swing outwards or inwards in relation to the rotor and in swung-out position having the type situated in a plane at right angles to the axis of the rotor, the said plane being identical for all the type bars, means to cause the rotor to revolve at regular rate of revolutions, a releasable locking device for each type bar placed on the rotor and in locking position holding the type bar in swung-in position and when open releasing the type bar so that it may swing outwards, a projecting arm for each type bar pivoted on the rotor on an axis parallel or almost parallel to the rotor axis, a connecting link between the said arm and the locking device, so that when the arm is swung in one direction the locking device will be moved into locking position and by the swinging of the arm in the opposite direction into release position, the said projecting arms being placed each in its plane at right angles to the axis of the rotor, a key for each type bar mounted on the frame, an engagement device for each key and the corresponding projecting arm movable between a position in which it will be in the track of the arm and a position in which it will be outside the track of the arm, and connecting media be-

tween each key and the corresponding engagement device so that when the key is depressed the engagement device will be carried into the track of the arm and when the key returns to initial position the engagement device will be carried out of the track of the arm.

5 2. Typewriter as claimed in claim 1, in which the type bars in swung-in position will be to all intents and purposes at a tangent to the rotor.

10 3. Typewriter as claimed in claim 1, in which at least part of the type bars in swung-in position will be in one and the same plane at right angles to the axis of rotation of the rotor.

15 4. Typewriter as claimed in claim 1 in which each type bar is provided with a fixed disc with two notches angularly off-set in relation to each other, and in which each locking device comprises a pivoted arm provided with a member which may engage and disengage either notch.

5 5. Typewriter as claimed in claim 1 in which the engagement device connected with the key is resilient in the 20 direction of rotation of the rotor.

6. Typewriter as claimed in claim 1 in which the type bars are so placed that their pivots will be almost parallel to the axis of rotation of the rotor.

25 7. Typewriter as claimed in claim 1 in which the type bars are placed on pivots forming a slight angle to the axis of rotation of the rotor.
